Primary Examiner — Kelley Donnelly(74) *Attorney, Agent, or Firm* — Raymond Sun**CLAIM**

The ornamental design for a modular utility rack, as shown and described.

DESCRIPTION

FIG. 1 is a perspective view of a modular utility rack showing my new design;

FIG. 2 is a front plan view thereof;

FIG. 3 is a right plan view thereof;

FIG. 4 is a left plan view thereof;

FIG. 5 is a top plan view thereof;

FIG. 6 is a bottom plan view thereof; and,

FIG. 7 is a rear plan view thereof.

1 Claim, 7 Drawing Sheets(56)
